CURTAIN STRETCHER CLAMP

Clarence G. Carlson, Chicago, Ill., assignor to
 Chicago Curtain Stretcher Company, Chicago,
 Ill., a corporation of Illinois

Application January 31, 1933. Serial No. 654,440

5 Claims. (Cl. 45—24)

This invention relates to clamps for adjustably securing the corners of a curtain stretcher frame and the like, the principal object being to lock the adjoined rails of a curtain frame against slipping when the clamp is tightened. The present device is advantageous in that it is exceedingly simple, may be operated with facility to clamp adjoined frame rails in desired positions of adjustment, and is otherwise effective for the purposes for which it is designed.

A suggestive embodiment of my invention is illustrated in the accompanying drawing in the manner following:

Figure 1 is a view in elevation of a corner of a curtain frame showing two adjoined rails locked by the present clamp;

Fig. 2 is an enlarged detail in transverse section on line 2—2 of Fig. 1;

Fig. 3 is an enlarged detail in section on line 20 3—3 of Fig. 1;

Fig. 4 is a detail in section on line 4—4 of Fig. 3; and

Fig. 5 is a view in perspective of the contact plate.

25 A curtain stretched frame with which the present clamps may be associated comprises certain rails of which two, A and B, are shown. The rail B is rested against the end of the rail A, and by the present clamping device may be secured in a desired position of adjustment. Similar clamps are provided at each of the corners of the frame.

The clamp consists of the metal strap s which is bent into the general form of a loop. The looped end 6 is extended out beyond one end of the rail 35 A, and the two legs 7 and 8 of the strap are disposed in parallel relation along opposite sides of the same rail to which they are secured as by rivets 9 and 10. The strap loop is thus extended not only beyond the end of the rail A but around 40 the adjoined rail B when the latter is placed against the end of rail A, as shown in Figs. 1, 2 and 4.

I provide a contact plate 15 having parallel slots 16 near its opposite ends. These slots are 45 aligned with the two legs of the strap so that the latter may extend through the slots whereby to guidingly support the plate. A slight offset 17 in one of the strap legs serves as a stop to limit movement of the contact plate in one direction.

Through the two legs of the strap near the looped end I provide aligned holes 20 furnishing a pivotal mounting for a cam device c which may conveniently be made of round wire. The 55 portion of the wire extending between the two

strap legs is crimped to provide a cam surface 21 which is engageable with opposite edges 22 of a slot 23 formed in the plate between the two end slots 16. Adjacent one end of the slot is a struck-up lug 24 serving as a stop for the cam. 60 One end of the wire is turned in line with its own axis to provide a trunnion 25 which is journaled in one of the holes 20. Opposite the trunnion end the wire continues axially as at 26 and is then turned laterally to provide an eye 27 which serves as an operating handle. A wire cam device of the kind described may be confined rotatively in place, with the two strap legs furnishing bearings therefor, and when so secured is non-displaceable from its mounting. 70

When the rail B is fitted within the looped end of the strap so as to lie against the end of the rail A, the contact plate is slipped back to a position adjacent the outer face of the rail B. To lock the two rails in a desired position of 75 adjustment, the handle 27 is manipulated to rotate the cam device so as to bring its crimp into engagement with the contact plate. The final position to which the cam device is movable is reached when the latter comes to rest 80 against the stop 24. The position of the stop is desirably such as to limit movement of the cam to a position just past center as shown in Fig. 4. When so positioned, pressure is maintained by the cam against the contact plate and the rail B whereby to clamp the latter against the end of the rail A so as to prevent relative movement therebetween. 85

The present device may be operated repeatedly with little or no wear on the parts which are engaged. In addition, it obviates many of the objections which inhere in a screw mechanism. For all purposes, including ready adjustment of the rails of a curtain stretcher frame, the present clamp is admirably suited, and its rugged simple character will assure dependable service over a long period of time. 95

I claim:

1. In combination with a frame rail, a strap which is looped to provide parallel legs engageable with opposite sides of the rail, means for securing the strap to the rail with its looped end extended beyond the end of the rail against which a second frame rail is slidably receivable 100 within the strap loop, a contact plate slotted to receive therethrough the strap legs and guidingly supported thereby adjacent one face of the frame rail last named, and a cam device pivoted to swing between the strap legs and against the 105

110 portion of the wire extending between the two

- contact plate to clamp the latter against the second frame rail.
2. In combination with a frame rail, a strap which is looped to provide parallel legs engageable with opposite sides of the rail, means for securing the strap to the rail with its looped end extended beyond the end of the rail against which a second frame rail is slidably receivable within the strap loop, a contact plate slotted to receive therethrough the strap legs and guidingly supported thereby adjacent one face of the frame rail last named, and a wire extending between the strap legs having therebetween a crimp preventing its endwise movement, the wire crimp serving also as a cam to engage the contact plate when the wire is moved to rotative position requisite for this purpose, the contact plate being thereby clamped against the second frame rail.
3. In combination with a frame rail, a strap which is looped to provide parallel legs engageable with opposite sides of the rail, means for securing the strap to the rail with its looped end extended beyond the end of the rail against which a second frame rail is slidably receivable within the strap loop, a contact plate slotted to receive therethrough the strap legs and guidingly supported thereby adjacent one face of the frame rail last named, and a wire extending between the strap legs having therebetween a crimp preventing its endwise movement and a lateral bend forming a handle exteriorly of the strap loop, the wire crimp serving also as a cam to engage with the contact plate when the wire is moved to rotative position requisite for this purpose.
4. In combination with a frame rail, a strap which is looped to provide parallel legs engageable with opposite sides of the rail, means for securing the strap to the rail with its looped end extended beyond the end of the rail against which a second frame rail is slidably receivable within the strap loop, a contact plate slotted to receive therethrough the strap legs and guidingly supported thereby adjacent one face of the frame rail last named, a wire extending between the strap legs having therebetween a crimp preventing its endwise movement, the wire crimp serving also as a cam to engage the contact plate when the wire is moved to rotative position requisite for this purpose, whereby the contact plate is clamped against the second frame rail, and means integral with the contact plate forming a stop by which to limit movement of the cam to a desired position.
5. In combination with a frame rail, a strap which is looped to provide parallel legs engageable with opposite sides of the rail, means for securing the strap to the rail with its looped end extended beyond the end of the rail against which a second frame rail is slidably receivable within the strap loop, a contact plate guidingly supported by the strap legs adjacent one face of the frame rail last named, and a cam device pivoted to swing between the strap legs and against the contact plate to clamp the latter against the second rail.
